UNITED STATES PATENT OFFICE.

WILLIAM HENRY STROUSE, OF OSKALOOSA, IOWA, ASSIGNOR TO W. H. STROUSE MANUFACTURING COMPANY, OF OSKALOOSA, IOWA, A CORPORATION OF IOWA.

MECHANICAL STOKER.

No. 840,722.

Specification of Letters Patent.

Patented Jan. 8, 1907.

Application filed September 16, 1905. Serial No. 278,753.

To all whom it may concern:

Be it known that I, WILLIAM HENRY STROUSE, a citizen of the United States of America, residing at Oskaloosa, in the county 5 of Mahaska and State of Iowa, have invented certain new and useful Improvements in Mechanical Stokers, of which the following is a specification.

This invention relates to mechanical stokers, and more particularly to that class of mechanical stokers adapted for use on locomotive-engines, the present improvements relating more specifically to the operating mechanism for the fuel-feeding plunger, the construction of the plunger itself, in connection with the door through which the fuel is passed, and to the means for overcoming shock incident to the reciprocations of the plunger.

The objects of the invention are to provide a simple practical form of stoker which may be applied to locomotives as at present constructed without material alteration in the fire-box or parts associated therewith and which will effect automatically, but under manual control, a uniform distribution of the fuel over the entire grate-surface.

The invention consists in certain novel details of construction and combinations and arrangements of parts, all as will be now described, and pointed out particularly in the appended claims.

In the accompanying drawings, Figure 1 is a side elevation of a stoker in position in front of a locomotive fire-box, portions of the apparatus itself and the front wall of the fire-box being shown in section. Fig. 2 is an elevation looking at the outer end of the stoker shown in Fig. 1. Fig. 3 is a longitudinal section in a substantially vertical plane and looking toward the right in Fig. 2, the dotted line 3-3 in Fig. 4 indicating the section-line. Fig. 3^a is a detail section of the spreader connections and lock therefor. Fig. 4 is a section in a vertical plane in right angles to Fig. 3, the section being on the line 4-4, Fig. 1. Fig. 5 is a plan view, partly in section and showing one form of spreader used in connection with a reciprocatory plunger. Fig. 6 is 45 a detail sectional view through the steam-chest to show the arrangement of ports and passages. Fig. 7 is a side elevation showing

a fuel-conveyer and driving mechanism therefor for use in connection with the stoker. Fig. 8 is a detail elevation of the valve-operating rock-shaft and arms connected thereto, the frame and plunger being shown in section. Fig. 9 is a detail section through the throttle-valve and showing the operating connections in dotted lines.

Like characters of reference in the several figures indicate the same parts.

Generally speaking, the operating parts of the stoker embody a reciprocatory plunger adapted to work through a front opening in the fire-box and to push fuel ahead of it from the bottom of a suitable hopper. The momentum imparted to the fuel by the plunger is sufficient to project the same to the desired points, and even distribution is effected by a suitable formation given to the end of the plunger and in some instances by making the end faces of said plunger movable to effect lateral distribution. The plunger itself is steam-actuated and reciprocates at a high speed, its reciprocations, however, being at all times under effective manual control, so that its movements may be limited in extent or speed at the will of the fireman.

In the said drawings the letter *a* indicates the front wall of a fire-box having a suitable fuel-opening therein, and the stoker is mounted against and in front of said wall, with its bed *A* projecting into the opening. The said bed *A* is preferably provided with upwardly-extending side flanges *B*, which form the guideways for the reciprocatory plunger *H*, which latter is adapted to advance into the furnace beyond the end of the bed *A* a suitable distance to secure the desired projection of the fuel into the fire-box. Surrounding the said bed *A* and surrounding the forward end of the plunger when retracted is a hopper *A'*, into which the fuel is placed in quantity as desired. The opening through which the plunger passes into the fire-box is normally closed by a door *b*, hinged at its upper edge in bearings *c* and resting in an inclined position, with its lower edge against the bed *A* and between vertical flanges *b'*, so as to effectually close the opening against the admission of air or fuel, save when the plunger *H* is advanced so as to push the door open. The said door *b* is usually arranged to

rest against inclined ribs B', and to insure quick and effective closing it is provided with an arm d , to the outer end of which a spring e is attached and suitably anchored at its opposite end, the arrangement being such as to reduce the weight of the parts as far as possible to overcome the effect of inertia, inasmuch as it is designed that the apparatus shall operate at relatively high speed and a heavy or weighted door would be ineffective by reason of the inertia to be overcome by the rapidly-moving plunger and the momentum acquired by the door itself when moved by the plunger.

15 Arranged parallel with the plunger and preferably close beneath the same and between its downwardly-extending sides is a steam-cylinder C, having a piston and piston-rod m working therein, the forward end 20 of the piston-rod being connected with the plunger, as will be hereinafter described and as illustrated in Fig. 1. The upper part of the cylinder and piston are between the depending side walls of the plunger at its rear end, whereby the piston-rod and piston are brought horizontally into alinement with the forward end of the plunger, and consequently direct pressure applied through the piston-rod does not tend to lift or push the plunger 25 out of alinement. This is an important consideration where high speed is contemplated or where the resistance to the movement of the plunger is irregular and indefinite in its points of application to the plunger, as is necessarily the case in handling coal or similar fuel having hard lumps and fine particles intermingled.

30 Means are provided for automatically controlling the admission of steam alternately to opposite sides of the piston in order to effect the reciprocation of the plunger, and such means embody a manual control, whereby the range of the reciprocations may be varied, their speed increased or decreased, as desired, and the plunger brought to rest invariably in its retracted position. In addition means are provided for automatically cushioning the piston at each end of its reciprocation, whereby the momentum is 35 checked without shock or noise.

To accomplish the last-mentioned end, the cylinder is provided with a longitudinal live-steam chamber c^3 , which is in communication at all times with the boiler, and this 40 chamber c^3 communicates at each end through ports c^5 with the ends of the cylinder C, the ports c^5 being normally closed, however, by outwardly-opening valves c^6 , having stems c^7 projecting into the cylinder and in 45 position to contact with the piston to open the valve when the piston approaches the end of the cylinder, thereby admitting live steam in front of the piston to check movement, and this action, it will be noted, takes 50 place entirely independent of the normal ad-

mission and exhaust of the steam for operating the piston.

Steam is admitted and exhausted from opposite ends of the cylinder for operating the piston through passages a' b' , leading to opposite ends of a valve-chest D, the ports into the valve-chest being preferably arranged, as shown at E³, from annular chambers E⁴, with which the passages a' b' communicate. The form of valve illustrated is a balanced piston-valve embodying heads d' d'' , connected by a valve-rod d , which extends out into position to coöperate with the operating mechanism to be presently described. Live steam is admitted to the valve-chest through an opening 55 F⁵¹, Figs. 4 and 6, from the manually-controlled valve E, Fig. 4, to which the steam is led from the boiler through a pipe S, and the exhaust from the valve-chest takes place through ports f at each end leading into a 60 common exhaust-chamber F and thence out through the exhaust-port F⁵. The proportioning of the parts is such that when the valve is moved to one extreme one of the passages a' b' is put into communication with 65 the exhaust and the other of said passages is in communication with the live-steam chamber of the valve-chest, and when the valve is moved to the opposite extreme the conditions just described are reversed, the result 70 being that the piston is reciprocated by the alternate admission and exhausting of the steam at opposite ends of the cylinder in the well-understood manner.

The valve-stem d is connected with an arm 75 I' on a rock-shaft I, and the latter is connected with the operating mechanism controlled by the movements of the plunger. This operating mechanism consists, primarily, 80 of two levers g and g' , arranged at opposite sides of the cylinder and near the under side of the plunger. The lever g is pivoted at its inner end at g^7 , Fig. 1, and the lever g' is pivoted at its outer end at g^8 , Fig. 3. The free end of the lever g' is connected, through a 85 link i^2 and arm i , with the rock-shaft I, (see Fig. 3,) and the lever g is connected, through a link i^3 , intermediate lever i^4 , link i^5 , and arm i^6 , with the said shaft, as shown in Fig. 1 of the drawings. Depression of the free end 90 of either one of the levers will move the rock-shaft, the lever g turning the said shaft in one direction and the lever g' in the opposite direction when depressed. On the under side 95 of the plunger and over the levers are blocks 100 G G', having faces inclined in opposite directions, the block G' over one of the levers being adapted to contact with a movable projection g^3 when the plunger is retracted and the inclined face of the block G being adapted 105 to contact with a movable projection g^2 on the other lever when the plunger is projected. (See Figs. 1 and 3.) Thus the levers will be 110 alternately depressed by the plunger in its reciprocations and the valve will be oper- 115 120 125 130

ated to admit steam to move the piston in one direction or the other, depending upon the movement of the plunger.

The movable projections g^2 g^3 on the levers 5 may be provided with antifriction-rollers, as shown, for engagement with the blocks or inclines on the plunger, and it is obvious that by shifting the said projections on the levers the range of movement of the plunger may 10 be varied at will. The projection g^3 , which controls the shifting of the valve when the plunger is at the rear end of its stroke or retracted, is preferably connected, through a link E^2 and arm k , Figs. 2 and 4, with a controlling hand-lever K , and said hand-lever K is connected, through a crank-arm E^2 , with the throttle-valve E , as shown in Figs. 1, 2, and 9. The arrangement is such that the projection g^3 is moved out of range of the incline G' before the valve is entirely closed, and consequently the plunger and piston are invariably brought to rest with the plunger in its retracted position, because, while steam is still admitted to the cylinder, the 25 shifting mechanism is moved out of engagement for shifting the valve when the piston is at the outer end of its movement, and the parts are brought to rest in this position, the final closing of the valve E only being effective to cut off the admission of steam to the valve-chest.

The movable projection g^2 on the lever g is connected, through a link k' , with an arm k^2 on a rock-shaft k^2 , Figs. 1, 2, and 8, and the 35 rock-shaft has upon its end a hand-lever K^2 , adapted to be locked in position by a suitable pawl and notched segment K^2 . The hand-lever K^2 and projection g^2 have a relatively wide range of movement, their function being to determine the inward throw of the plunger, and it is obvious that by shifting the hand-lever so as to move the projection g^2 rearwardly from the forward end of the 40 plunger the forward movement of the plunger will be arrested at an earlier period in its reciprocation, and consequently by the simple manipulation of the hand-lever K^2 the fireman may cause the plunger to project the fuel to the extreme back end of the furnace 45 by long and rapid movements, or should the front portion of the furnace require additional fuel the movement of the plunger may be restricted, so as to project the fuel only over the said front portion, although in the normal and ordinary operation of the device and 50 with ordinary fuel the parts may be set to give the plunger a definite throw and still distribute the fuel uniformly over the entire grate area.

60 In the preferred form of plunger illustrated herein the forward end or nose of the plunger is formed by diagonally-arranged spreaders or deflecting-faces K^2 , which come to a point or apex at substantially the center 65 line of the plunger, as well illustrated in Fig.

5, each face or spreader terminating at its lower edge in a forwardly and laterally extending base-flange K^2 . The inclined faces of the spreaders serve to throw the fuel to the sides of the fire-box as the plunger advances, 70 and the base-flanges serve to in a measure support the fuel until the desired momentum is imparted to it. Inasmuch as it is desirable in some cases to project a greater quantity of the fuel transversely or toward the 75 sides of the furnace, the said spreaders are preferably hinged at their rear edges to the sides of the plunger H , as shown at j , Fig. 5, and they are connected by links L , pivoted in lugs k^2 on the spreaders, with a head M on the 80 piston-rod m ; the object being to cause said spreaders to swing laterally as soon as they move out from between the guiding-flanges B . Means are provided, however, for preventing the pivotal action or swinging of the 85 spreaders unless so desired by the attendant and, as shown in the drawings, this means consists of the locking-lever P , Fig. 3, against which the head M normally rests. The lever P is held in position by a rod p , extending 90 back to the rear end of the plunger through guides Q and provided at its rear end with a projection r , adapted to engage a shoulder on the plunger. It is also provided with a handle q , by means of which the projection may 95 be disengaged from the shoulder when it is desired to release the spreaders and permit them to act as before described.

As a convenient means for supplying fuel to the hopper A' the hopper is provided with 100 an extension 10, Fig. 7, into which a conveyer 8, leading from a suitable source of fuel-supply, is adapted to pass, said conveyer running over sprocket-wheels or pulleys 7 and 9 and one of the latter being driven 105 through drive-chains 4 and 6 from a motor, such as a turbine-engine, (indicated at 2 in Fig. 7); but it will be understood that any other suitable arrangement of conveyer may be employed for keeping the hopper 110 constantly provided with fuel, inasmuch as it is quite desirable in the operation of the stoker that the hopper should be filled with fuel to a point above the level of the plunger, so that the fuel itself operates in a measure to prevent any undue access of air at the instant when the plunger is moving into or out of the furnace and at which time neither the door nor plunger can constitute a perfect seal for the opening.

Having fully described the invention, what I claim as new, and desire to secure by Letters Patent, is—

1. In a mechanical stoker, the combination with a reciprocating plunger located 125 above the level of the bottom of the fire-box and having a fuel-projecting nose on its forward end; of a plunger-operating mechanism embodying a hand-lever-controlled means for varying the extent of the forward stroke 130

of the plunger during its operation to project the fuel a greater or less distance as desired.

2. In a mechanical stoker, the combination with a reciprocatory plunger located 5 above the level of the bottom of the fire-box and having a fuel-projecting nose on its forward end, of a plunger-operating cylinder and piston, a valve controlling the admission and exhaust ports of the cylinder, a valve-gear operated by the plunger and embodying a hand-lever-controlled means for varying the extent of the forward stroke of the plunger during its operation to project the fuel a greater or less distance as desired.

15 3. In a mechanical stoker, the combination with a reciprocatory plunger located above the level of the bottom of the fire-box and having a fuel-projecting nose at its forward end, of an elastic-fluid motor for reciprocating the plunger, a valve therefor and a valve-gear embodying a hand-lever-controlled means for varying the extent of the forward stroke of the plunger during its operation to project the fuel a greater or less 25 distance as desired.

4. In a mechanical stoker, the combination with a reciprocatory plunger located above the level of the bottom of the fire-box and having a fuel-projecting nose at its forward end, of an engine embodying a piston connected directly with the plunger and means for automatically reversing the forward movement of the plunger and piston embodying a hand-lever-controlled means 35 for varying the point of reversal during the operation of the parts to project the fuel a greater or less distance as desired.

5. In a mechanical stoker, the combination with a reciprocatory plunger having a 45 fuel-projecting nose at its forward end and a plunger-operating piston and cylinder, of a valve controlling the admission and exhaust ports of the cylinder and a valve-operating gear embodying independent operating-levers for moving the valve in opposite directions and each having a projection thereon and inclines moving with the plunger for coöperating with said projections to shift the valve as the plunger nears the extremes of its stroke; substantially as described.

6. In a mechanical stoker, the combination with a reciprocatory plunger having a fuel-projecting nose at its forward end and a 55 plunger-operating piston and cylinder, of a valve controlling the admission and exhaust ports of the cylinder, a valve-operating gear embodying independent operating-levers for moving the valve in opposite directions and having movable projections thereon, hand-levers controlling the position of said projections on the levers and inclines moving with the plunger for coöperation with said projections to shift the valve; substantially as described.

7. In a mechanical stoker, the combination with a reciprocatory plunger having a fuel-projecting nose at its forward end and a plunger-operating piston and cylinder, of a valve controlling the admission and exhaust 70 ports of the cylinder, a valve-operating gear embodying independent operating-levers, independently-movable projections on said levers, oppositely-arranged inclines moving with the plunger for coöperation with 75 said projections to shift the valves and means for adjusting the relative positions of the projections and inclines to shift the valve at different points in the throw of the plunger; substantially as described.

8. In a mechanical stoker, the combination with a fuel door-frame and door, a reciprocatory plunger having a fuel-projecting nose adapted to work through the door-opening and a plunger-operating piston and cylinder, of valve mechanism for the cylinder embodying an admission and exhaust controlling valve and a throttle-valve, and a valve-gear embodying a lever controlling the throttle-valve and the operating connections for 85 the admission and exhaust valve at the rear end of the cylinder, whereby the piston will be brought to rest at the rear end of its stroke; substantially as described.

9. In a mechanical stoker the combination 95 with a fuel door-frame and door, a reciprocatory plunger having a fuel-projecting nose adapted to work through the door-opening, a reciprocating steam-engine for operating the plunger embodying a valve and valve-gear, of a throttle-valve, a hand-lever controlling the latter and connections between said lever and the valve-gear operating to throw the valve-gear controlling the advance 100 of the plunger out of operation prior to the closing of the throttle; substantially as described.

10. In a mechanical stoker, the combination with the fuel door-frame and door, the plunger having a fuel-projecting nose adapted 110 to work through the door-opening, cylinder and piston for operating the plunger, of a valve controlling the admission and exhaust ports of the cylinder, means whereby the movement of the plunger operates the valve 115 and means for releasing the valve from control of the plunger.

11. In a mechanical stoker, the combination with the fuel door-frame and door, the plunger having a fuel-projecting nose adapted 120 to work through the door-opening, cylinder and piston for operating the plunger, of a valve controlling the admission and exhaust ports of the cylinder, means whereby the movement of the plunger operates the valve, a lever adapted for manual operation and connections whereby a movement of the lever in one direction releases the valve from the control of the plunger to bring the plunger to rest and a movement in the opposite 125 130

direction moves the valve to open the admission-port.

12. In a mechanical stoker the combination with a reciprocatory plunger having a fuel-projecting nose at its forward end and a power mechanism for imparting a rapid reciprocation to the plunger, of a door-frame through which the plunger works having an inclined seat and a door hinged to said frame and resting against said seat in an inwardly-inclined position and adapted to be opened by the fuel advanced by the plunger; substantially as described.

13. In a mechanical stoker the combination with a fuel-hopper having a fuel-discharge opening near the bottom at one side, a door hinged at the top of said opening and extending downwardly on an incline away from the hopper when in closed position whereby the fuel does not exert a pressure to open the door, and a reciprocatory plunger working through the bottom of the hopper and opening and operating to push fuel in front of it to open the door and to project the fuel into the furnace and a power mechanism for reciprocating the plunger.

14. In a mechanical stoker, the combination with a furnace-wall having an opening therein a stoker-bed projecting into said opening and a reciprocatory plunger working on the bed having a fuel-projecting nose and operating mechanism for imparting a forward movement to the plunger to project its nose beyond the end of the bed, of a door hinged at the top of the opening and extending downwardly and inwardly in an inclined position to close the opening and adapted to be opened inwardly by the advance of the plunger; substantially as described.

15. In a mechanical stoker, a reciprocatory plunger, for projecting the fuel into the furnace having deflecting-faces oppositely and outwardly inclined to the line of move-

ment of the plunger and forwardly-extending fuel-supporting flanges at the lower edges of 45 said deflecting-faces; substantially as described.

16. In a mechanical stoker, a reciprocatory plunger for projecting the fuel into the furnace, having deflecting-faces pivoted at 50 the sides of the plunger and means for moving said faces on their pivots to project the fuel to the sides of the furnace; substantially as described.

17. In a mechanical stoker, a reciprocatory plunger for projecting the fuel into the furnace, having deflecting-faces pivoted at 55 the sides of the plunger, forwardly-extending flanges at the lower edges of the deflecting-faces and means for moving said faces on 60 their pivots to project the fuel to the sides of the furnace; substantially as described.

18. In a mechanical stoker, a reciprocatory plunger for projecting the fuel into the furnace, having pivoted inclined deflecting- 65 faces means for moving said faces on their pivots to project the fuel to the sides of the furnace and means for holding said faces against movement independent of the plunger; substantially as described.

19. In a mechanical stoker, a reciprocatory plunger for projecting the fuel into the furnace, having pivoted inclined deflecting- 70 faces, a plunger-operating mechanism connected with said faces to swing them on their pivots and means for holding said faces against independent movement; substantially as described.

In testimony whereof I affix my signature, in the presence of two witnesses, this 6th day 80 of September, 1905.

WILLIAM HENRY STROUSE.
